UNITED STATES PATENT OFFICE.

ERNST HENRY LENZ AND HARRY BELL, OF EVANSVILLE, INDIANA.

CLEANER ATTACHMENT FOR PLAYER PIANOS.

1,410,537.

Specification of Letters Patent. Patented Mar. 21, 1922.

Application filed August 31, 1920. Serial No. 407,145.

To all whom it may concern:

Be it known that we, ERNST HENRY LENZ and HARRY BELL, citizens of the United States, residing at Evansville, in the county 5 of Vanderburg and State of Indiana, have invented new and useful Improvements in Cleaner Attachments for Player Pianos, of which the following is a specification.

This invention relates to player pianos, 10 and has for its chief object the provision of an efficient and inexpensive attachment therefor, by means of which dust or other foreign matter which accumulates inside the tubes and elsewhere upon the piano may be 15 readily and easily removed by suction produced by the pneumatic system of the piano itself.

More specifically stated, the invention comprehends the provision of a valve like 20 mechanism through the instrumentality of which air currents of the player mechanism may be deflected or diverted so that suction may be created in the tubes of the cleaning device forming the subject matter of the invention.

The nature and advantages of the invention will be better understood when the following detail description is read in connection with the accompanying drawings, the 30 invention residing in the construction, combination and arrangement of parts as claimed.

In the drawings forming part of this application like numerals of reference indicate similar parts in the several views and wherein.

Figure 1 is a fragmentary view of a player piano showing the position of the attachment in use.

Figure 2 is a sectional view taken on line 40 2-2 of Figure 1 looking in the direction of the arrow.

Figure 3 is an elevation of the device removed showing the operative position of 45 parts.

Figure 4 is an edge elevation showing the inoperative position of the parts.

Figure 5 is a view similar to Figure 1 showing a modification of the invention.

The device forming the subject matter of 50 this invention embodies two blocks indicated at 10 and 11, which may be constructed from any suitable material preferably wood, and preferably of the design illustrated. The 55 blocks are of equal dimensions, except in thickness, their small ends being overlapped

and pivoted as at 12. Interposed between these blocks and secured to the block 11 is a piece of leather or other suitable material forming an air tight medium when the blocks 60 are moved one upon the other. The block 10 is provided with an elongated slot 14 to receive the element 15 which preferably is a screw secured to the block 11, and serving as a means for holding the block readily 65 together against the air-tight medium 13. Encircling the pivot 12 and also the pin 15 are coiled springs 17 with washers interposed between them and the block forming a base for the pressure of the springs 70 against the block 11, which yieldably hold the blocks properly and operatively associated. The block 10 is provided with an opening 18 in which is fitted a tube 19 which may be constructed from any suitable 75 material and secured in place upon the blocks. This tube forms a part of an air channel between the motor and the mechanism of the player valves and is engaged in a tube 20, which tube leads to the motor 80 of the piano. The block 11 is also provided with an opening 21 similar to the opening 18 in the block 10 and also forms a part of the air passage from the motor to the action valves of the piano, and receives the 85 tube 22 located on the tempo box 23 from which the hose or tube 20 has been removed. A relatively small tube 24 is secured to the block 10 being preferably made 90 of metal, extending far enough away from the block to accommodate a flexible hose 25. As clearly shown in the drawings, this tube 24 lies directly above the opening 21 in the block 11 thereby directing the suction into 95 the flexible hose 25.

A lever 26 is secured to the block 10 and is utilized for adjusting the blocks in a manner to be hereinafter described, this lever being of any desired length and constructed from any suitable material, it being 100 provided with an elongated slot 27 to receive a pin 28 carried by an operating rod 29 which terminates to provide a finger receiving ring 30, except where the device is placed so as to be operated by the hands in 105 which case the slotted operating rod is dispensed with. The operating rod reciprocates through suitable guides 31 secured to the underside of the key board of the piano. Associated with the flexible hose 110 25 is a short tube 32 which receives the dust or other foreign matter drawn from
